H. O. Harwood.

UNITED STATES PATENT OFFICE.

JOHN F. SCOTT, OF COHOES, NEW YORK, ASSIGNOR, BY MESNE ASSIGNMENTS, TO ARNOLD S. HATCH, OF ALBANY, NEW YORK.

COMBINATION GARMENT.

Application filed September 3, 1924. Serial No. 735,555.

To all whom it may concern:

Be it known that I, JOHN F. SCOTT, a citizen of the United States, and a resident of Cohoes, county of Albany, State of New York, have invented certain new and useful Improvements in Combination Garments, of which the following is a specification.

This invention relates to an article of wearing apparel and specifically to a combination garment for men, women and children.

The garment is particularly adapted for underwear, such as union suits, but is not necessarily confined to such uses because the invention is obviously applicable to other types of union or combination garments, such as athletic suits, pajamas and overalls.

In the interest of brevity the following description particularly pertains to union or combination garments for underwear, but as stated above, it is obvious that the same construction may be utilized in making the other garments above mentioned.

One of the objects of the invention is to provide a garment of the union or combination type in which it is not necessary to provide buttoning or fastening means ordinarily required to close the chest or back portions in garments of this type.

Another object of the invention is to provide a garment of the union or combination type which is, for the most part, constructed of non-elastic fabric, such as nainsook or other non-elastic woven fabric suitable for the particular purpose for which the garment is to be used or of practically non-elastic knitted fabric so that such a garment may be easily donned or taken off, and which will nicely fit the body of the wearer without the use of buttons or fastening means.

A still further object of the invention is to provide a garment of the type described in which the upper back portion and shoulder portions consist of elastic fabric preferably of knitted webbing, the shoulder portions being extended downwardly and around the arm pits, the garment being so constructed that the shoulder portions may be displaced laterally to permit the garment to be readily donned or removed by stepping into or out of it through the neck opening, yet when worn, the chest, shoulder and back portions are positioned to adequately cover and nicely fit the body of the wearer, the entire front portion of the gar-

ment being of the material of which the greater part of the garment is made.

Still further objects of my invention are to provide in garments of the type indicated, inserts having straight seams, at a right angle to the elasticity of the elastic fabric, between the elastic fabric and the more rigid inelastic fabric, and to provide a neat, smooth seam that will not be easily pulled apart.

With these and other objects in view the invention comprises the garment described and illustrated in the accompanying specification and drawings and defined in the claims.

The various features of the invention are illustrated in the accompanying drawings in which:

Fig. 1 is an elevation showing the front of a garment embodying my invention.

Fig. 2 is a similar view showing the back of said garment.

Fig. 3 is a fragmentary view in perspective partly broken away and partly in section of one side of the garment shown in Fig. 1.

Fig. 4 is a view of the upper portion of the garment (being broken away) the neck opening being stretched in order to don the garment by stepping into it, or to doff the garment; in this figure the stretched neck opening is bounded by the full lines and the dotted lines show the portions of the garment in place on the body of the wearer when donned.

Fig. 5 is a rear view of a modified structural form of the garment shown in reduced size.

Referring more particularly to the accompanying drawings, the front chest portion is designated 10, the back portion 11 and 12, shoulder portions 13 and 14, said shoulder portions continuing under the arms at 15 and 16, the side portions 17 and 18 and the leg portions 19 and 20. All of these portions with the exception of the arms and the upper back portion are constructed of woven, non-elastic fabric, such as nainsook, or other suitable woven, nonelastic fabric, or substantially non-elastic knitted fabric.

Extending across the upper portion of the back and bordering the neck opening 0 is an elastic knitted fabric 12. This fabric may extend downwardly a distance of either, two, four, six or eight inches. The repre-

sentation shown in Fig. 2 shows one of the minimum sizes for the knitted fabric situated in the back, and Fig. 5 shows the maximum size where the knitted fabric extends 5 substantially down to or slightly below the arm pits.

The upper edge of the knitted fabric 12 borders the neck opening at 21, and the inner edges of the shoulder straps 13 and 14 10 border the neck opening at 23 and 25. The lower portions 15 and 16 of the shoulder straps extend under the arm pits at 27 and 29, thus serving the double function of providing elastic shoulder straps and the im- 15 portant function of absorbing undue perspiration usually found under the armpit.

The various parts of the garment are stitched together on the seams as shown in the drawing, the back insert 12 being sub- 20 stantially rectangular in shape, thus avoiding the diagonal seams between two kinds of fabrics. In fact, the only seam be- 25 tween the two kinds of fabrics consists of a single horizontal seam at 30, against which the strains are at a minimum.

This feature of having the seams run straight and not on a bias with the ribs or weaving of the elastic material is of 30 importance in that it provides a joint much less liable to pull apart than is the case when a seam is made on a bias to the knitted fabric. Moreover, a much smoother and sightlier seam can be made with a seam at 35 right angles to the ribs of the woven material than when the seam is on a bias there- with.

As indicated more particularly in Fig. 3, the knitted fabric 12 is doubled with the 40 folded edges at the top, forming an edge of the neck opening, and the top edge 31 of the relatively inelastic fabric 11 is inserted between the lower edges 32 and 33 of the elastic fabric 12 and stitched in position. This form of seam is particularly 45 firm and smooth and easy to launder.

As will be seen from the above, the union 50 suit or combination garment has an entirely smooth front of fabric which is either non- elastic or of very limited elasticity extending from the top of the neck to the bottom of the leg and around the sides with a substantially rectangular insert running cross-wise in the back of the garment, across the shoulder bordering the neck opening 55 which is of relatively greater elasticity particularly in a lateral direction. In addition, elastic shoulder straps are provided, which extend under the arm pits for the purposes described.

60 As clearly shown in the drawing, the garment may be donned or taken off the body of the wearer by stretching the shoulder portions 13 and 14 outwardly in the direction of the arrows therein shown, thus 65 stretching the upper portion of the elastic

knitted web insert 12 so as to extend the neck opening 0 into a body opening which may be drawn up over the body of the wearer when the garment has been stepped into the usual manner of donning a union or combination garment. Conversely, the same stretching of the neck opening of the garment is effected in order to remove it from the body of the wearer.

The elastic insert runs the entire width 75 of the back at the shoulders of the garment and may be made in various lengths from top to bottom, as specified above; that is, starting from the top of the shoulder and extending downwardly and does away with 80 the usual method of putting inserts in the back or center of the garment above the hips which are difficult to sew in and which have a tendency to unduly stretch out of 85 shape by reason of the fact that the wearer when sitting down gives the garment a great strain or pull. My new invention avoids this objection and gives a continuously smooth fitting garment of the same proportions. The depth of the elastic insert at 90 the top portion of the back is governed in accordance with the kind and elasticity of 95 the cloth used.

One of the chief purposes of the elastic 100 inserts in the back in addition to permitting the garment to be put on by stepping into it, or taken off by passing the garment over the body, is that this elastic knitted material is absorbent and thus avoids the uncomfortable feeling which occurs at the 105 back by the use only of a substantially rigid cloth, such as nainsook or other of the hard finished fabric.

It is a well known fact that rigid fabrics, 110 such as chiefly used in the manufacture of union suits called nainsook union suits, do not absorb the perspiration caused by contact with the body and as the principal pressure is across the back right over the shoulder by reason of the clothing which is 115 worn outside, the back of the suit is always moist and uncomfortable, as these rigid fabrics retain the perspiration and do not absorb it like a knitted fabric, such as is used 120 in the garment embodying my invention.

A further and important feature is the 125 elastic webbing used around the armhole which also forms the strap holding the garment in position over the shoulder. This serves the double purpose of furnishing an increased elasticity and provides an easy way of donning or doffing the garment without any strain on the fabric, such as usually found in rigid or nainsook union suits, and furthermore performs the important function of absorbing undue perspiration usually found under the armhole.

A further advantage in the construction 130 of the garment is due to the fact that the elasticity which the garment affords cross-

wise of the shoulder, by the elastic insert in the back, permits great elasticity across the shoulder when moving the arms forward as in reaching for something or exercising, an elasticity which is never found in nainsook garments made in the ordinary manner. This additional elasticity avoids the undue strain usually found in other constructions and adds greatly to the durability of the garment.

The garment furthermore is exceedingly economical from the standpoint of manufacture and withstands ordinary wear of laundering to a maximum degree.

15 The garment may be finished in the usual way with the ribbed edges and the arm, leg and neck portions being provided with the usual border. The garment may also be provided with the fly and overlapping seat portions common to union suits.

20 As changes of construction could be made within the scope of my invention, it is intended that all matter contained in the above description or shown in the accompanying drawings be interpreted as illustrative and not in a limiting sense.

Having thus described my invention what I claim as new and desire to secure by Letters Patent is:

30 1. A combination bifurcated garment, the trunk or body portion of which is constructed of substantially non-elastic fabric, the said non-elastic fabric extending around the sides, shoulder straps of elastic material

35 continued about the arm holes of the garment to form an elastic border therefor, the upper edges of the non-elastic material lying within the space between said arm holes,

and an insert of elastic material secured on a horizontal line to said non-elastic material 40 at the back of the garment and extending upwardly between the elastic borders of said arm holes for a substantial distance and secured thereto and forming a border for the neck opening and having its ribs extending vertically to provide a relatively great elasticity in a lateral direction to enable the neck opening to be enlarged sufficiently to permit the body of the wearer to pass therethrough and to enable the garment to contract about the neck of the wearer.

45 2. A combination bifurcated garment the trunk or body portion and the leg portions of which are constructed of a non-elastic fabric, said fabric extending around the 50 sides and under the arms, borders of elastic material about the arm holes of said body portion and extending upwardly therefrom to form shoulder straps, and an insert of laterally elastic vertically ribbed material in the upper portion of the back of said body 55 extending downwardly from the neck opening between said arm hole borders and secured thereto, said fabric being doubled with the doubled edge at the upper portion 60 bordering the neck opening at the upper portions of said border portions and having the upper edge of the relatively inelastic material inserted between the lower edges and joined thereto on a straight, substantially horizontal, seam extending between said arm hole borders, the upper edge of 65 said insert forming a neck opening border lying above the lower edges of the arm hole.

70 JOHN F. SCOTT.
